ABSTRACT OF THE DISCLOSURE

A process for making a dicarboxylic acid having 21 carbon atoms from fatty acids is accomplished by reacting the linoleic acid portion in a fatty acid mixture with up to 26% by weight of fatty acids of acrylic acid and with from 0.01% to 0.5% by weight of fatty acids of iodine catalyst at a temperature between 200° C. and 270° C. The fatty acid-dicarboxylic acid mixture is then separated by distilling into an oleic-type fatty acid and a C₂₁ dicarboxylic acid. This process is especially applicable to separating tall oil fatty acids.

BACKGROUND OF THE INVENTION

This invention relates to the production of a dicarboxylic acid having 21 carbon atoms. It also relates to a process for the separation of fatty acids. More specifically, this invention relates to a process for making dicarboxylic acid having 21 carbon atoms from tall oil derived linoleic acid. As used herein the term "dicarboxylic acid" is intended to mean a dicarboxylic acid having 21 carbon atoms, but in some instances includes minor amounts of dicarboxylic acid or other molecular weights.

The invention outlined below is to be distinguished from treatment of tall oil fatty acids with iodine as set forth in U.S. Pat. 3,157,629 to P. D. Patrick. In the Patrick process, tall oil fatty acids are heated within a range of 450–550° F. (232° C.–288° C.) in the presence of an iodine catalyst until the linoleic acid portion of the fatty acid is reduced below 15%, forming saturated acids, primarily oleic acid and 2–25% dimerized acids. In contrast, in the process of this invention, the linoleic acid is not converted to oleic acid. The process of this invention is also to be distinguished from U.S. Pats. 2,617,792 to Floyd, and 2,811,386 to Hasselstrom. In these processes, the tall oil starting material contains a relatively large proportion of rosin acids and is subjected to heat in the presence of a catalyst, whereupon hydrogen is generated largely from the rosin acids and serves to hydrogenate certain rosin acids as well as the unsaturated fatty acids. The reactions above do not accomplish the results of this invention.

The use of dicarboxylic acids is well known in the prior art as dicarboxylic acids are useful as plasticisers in the manufacture of alkyd resins and as curing agents for epoxy resins. A process for making dicarboxylic acid from fatty-type acids is disclosed in British Pat. No. 1,032,363, wherein conjugated fatty acids are isomerized to a trans/trans form with iodine and subsequently reacted with a reactive dienophile to form the Diels-Alder adduct. However, the disclosed reaction has heretofore not been applied to fatty acids containing non-conjugated linoleic acid wherein the non-conjugated linoleic acid is converted to dicarboxylic acid.

It is therefore a general object of this invention to provide a process for making dicarboxylic acid from all of the available linoleic acid in a fatty acid mixture. Another object of this invention is to provide a process whereby tall oil fatty acids may easily be separated into a dicarboxylic acid portion and an oleic acid-type portion.

Other objects, features and advantages will be evident from the following disclosure.

2**SUMMARY OF THE INVENTION**

It has been found that if a fatty acid mixture containing a significant portion of linoleic acid is treated with up to 26% by weight of fatty acids of acrylic acid and from 0.01% to 0.50% by weight of fatty acids of iodine at a temperature between 200° C. and 270° C., the linoleic acid portion of the fatty acid mixture is converted to dicarboxylic acid. Thus when the fatty acid mixture is a tall oil fatty acid mixture, and stabilized glacial acrylic acid, and iodine catalyst are heated together at 230° C.–250° C. for about one to two hours, they produce a dicarboxylic acid along with the residual monounsaturated and saturated fatty acids. Upon distillation, a high grade oleic acid is obtained; the residue being dicarboxylic acid. Such separation of the oleic and linoleic acids in tall oil is not possible by fractional distillation of the fatty acids prior to reaction with acrylic acid.

**DETAILED DESCRIPTION OF THE
INVENTION**

There is provided by this invention a convenient process for upgrading crude and distilled fatty acids by forming different acids from one portion of the fatty acid and separating the fatty acids into distinct major fractions. Until this invention, it has been difficult to fractionally distill tall oil fatty acids into component acids because of their close boiling points. The invention is based on conversion of the total diene portion of fatty acids to dicarboxylic acid, which has a significantly higher boiling point than oleic acid.

Accordingly, tall oil fatty acids containing both non-conjugated and conjugated linoleic acid are reacted with acrylic acid in the presence of catalytic amounts of iodine. The acrylic acid is added to the fatty acid mixture in an amount up to about 12% by weight of fatty acids. The catalytic amounts of iodine used is from 0.01% to 0.50% based on the weight of fatty acids, preferably 0.05%–0.2% by weight. The upper amount gives rapid reaction without unnecessary loss of color. If large percentages of iodine are used, i.e., above 0.5%, or if the reaction temperature is increased above 270° C. a portion of the linoleic acid is converted to oleic acid and the yield of dicarboxylic acid is thereby decreased. There is a lower limit of feasibility too, for at just slightly milder reaction conditions the rate drops to almost zero. In order to maintain the highest possible yield of dicarboxylic acid from a mixed fatty acid, conditions close to the lower catalyst level and lower temperature are maintained. Selection of the ideal amount of catalyst will depend on the equipment, temperature and time of the reaction. The reaction to produce dicarboxylic acid is carried out at a temperature between 200° C. and 270° C., preferably 230° C.–250° C. The reaction time at these temperatures and under the preferred catalyst level is about one to two hours.

The following is typical of the general procedure which may be used in carrying out the process of this invention on tall oil fatty acids.

To tall oil fatty acids is added up to 12% by weight of fatty acids of glacial acrylic acid and 0.1% by weight of fatty acids of iodine, at a temperature between 230 to 250° C. The acrylic acid catalyzed by iodine readily undergoes reaction with the fatty acids. Therefore, when tall oil fatty acids, acrylic acid and iodine are mixed together and heated to 250° C., the linoleic acid in the fatty acids is converted to dicarboxylic acid. In addition to the advantage of having a one step reaction in this case, it seems that the iodine catalyzes the addition reaction to get a very clean, rapid reaction. This one step process greatly improves the overall yield of dicarboxylic acid from fatty acids containing linoleic acid because all of the linoleic acid is immediately converted to dicarboxylic acid. The

amount of dicarboxylic acid formed is approximately the same as the starting content of linoleic in the fatty acid mixture. This process is equally applicable to fatty acids derived from sources other than tall oil, such as animal derived and vegetable derived fatty acid mixtures containing substantial amounts of linoleic acid.

One of the major advantages of this process is that tall oil fatty acids may be separated into two fractions by distillation. In a fractional laboratory distillation a 5% heads cut is taken and then, one gets 50% of the feed as distillate. The remaining 45% is dicarboxylic acid which can be further purified, if desired, by molecular distillation. Using the fractional distillation method of purification, a distillate which is very similar to oleic acid is obtained. This product is about 75% C_{18} monounsaturated fatty acids, has an acid number of 195, has only 3% diene, and has a titer of about 20° C.

The crude dicarboxylic acid material, which accounts for 45% of the total, is about 92% dicarboxylic acid.

tions A-D in Table I. As can be seen, the reaction occurs at 205° C., but for optimum utility and maximum yield of dicarboxylic acid within a reasonable time a temperature of about 250° C. is preferred. Reactions E-H show the effect of various catalyst levels and again a variety of addition levels will promote the reaction but these results are shown with 0.075% to 0.15% iodine.

The time required for maximum conversion of linoleic acid to dicarboxylic acid depends on temperature and catalyst level. As is demonstrated in reactions H-J, if the temperature is 250° C. and 0.15% iodine is used about 45 minutes is required for complete conversion of the linoleic acid in the tall oil to dicarboxylic acid. The gas chromatography data shows that only the linoleic acid is reacting (percentage decreasing). There is very little change in the fatty acids present in the tall oil except for the reaction of the linoleic acid, thus, one obtains a mixture of tall oil fatty acid (virtually linoleic free) and the dicarboxylic acid.

TABLE I

[Variations in reaction conditions for reaction of distilled tall oil fatty acids with acrylic acid]

Untreated fatty acid	Reaction number									
	A	B	C	D	E	F	G	H	I	J
A. Conditions:										
Temperature, ° C.	205	219	232	252	250	250	250	250	250	250
Percent iodine	0.06	0.06	0.075	0.06	0.075	0.1	0.125	0.15	0.15	0.15
Time, hrs.	2	3	2.5	2.5	2	2	1.2	1	0.5	0.75
B. Analysis by GLC assignment:										
Saturated fatty acid	5.1	5.1	5.0	4.4	4.3	4.5	4.6	4.6	4.1	5.8
C_{18} monounsaturated fatty acid	46.0	46.7	47.2	46.6	45.0	44.5	44.9	44.4	44.8	44.5
Linoleic acid	41.4	25.4	17.8	15.2	5.5	6.3	2.4	2.0	1.4	5.4
Other fatty acids	8.5	11.8	10.0	9.8	10.2	10.7	9.1	9.0	10.7	8.3
C_{21} dicarboxylic acid	0.0	12.0	20.0	24.0	35.0	34.0	39.0	40.0	40.0	36.0

The impurities are about 5% fatty acids and 3% dimer-type fatty acids. This material is rather dark since it is a bottoms product and must be purified to get a high grade dicarboxylic acid. The C_{21} dicarboxylic acid from linoleic acid with two acid groups is shown below. The theoretical acid number is 316 and that of the crude dicarboxylic acid is about 308 due to the impurities listed above which are present.

wherein one X is a hydrogen (H) and the other X is a carboxylic acid group (COOH).

Another means, other than molecular distillation, for purifying the crude dicarboxylic acid is by distillation of its methyl or dimethyl ester. At 0.2 mm. vacuum the dicarboxylic acid boils at 265° C., the monomethyl ester boils at 240° C., and the dimethyl ester boils at 220° C. Therefore, by converting the crude dicarboxylic acid to its dimethyl ester and then distilling, a very pure product can be obtained. The separation from dimer acid is very good too, since the dimethyl ester of any dimer acid present boils at least above about 260° C. The dimethyl ester and the monomethyl ester of the dicarboxylic acid are readily purified by fractional distillation; whereas the free dicarboxylic acid is best separated by molecular distillation.

The practice of this invention may clearly be seen in the following examples.

EXAMPLE 1

To illustrate the production of C_{21} dicarboxylic acid, a series of reaction involving the addition of acrylic acid to tall oil fatty acids were run. The reaction conditions and results are shown in Table I.

In these reactions 12% by weight of the fatty acids of glacial acrylic acid was added to the linoleic acid portion of distilled tall oil fatty acids in the presence of an iodine catalyst. The effect of temperature is illustrated by reac-

35

This example illustrates separation and characterization of C_{21} dicarboxylic acid. The acid mixture from the reaction of distilled tall oil fatty acids, iodine, and acrylic acid can be separated into three fractions by fractional distillation in a short path still with an inch of glass beads in it to serve as plates. From this distillation a 4% heads fraction (100% fatty acids); 50% distillate fraction (97.2% fatty acids, 2.8% dicarboxylic acid); and 45% residue fraction (4.7% fatty acids, 92.1% dicarboxylic acid, and 3.2% other) was obtained. The analysis of each fraction was by gas chromatography. The "other" portion of the residue fraction represents unidentified material which does not come out in the dicarboxylic acid peak. Most of this "other" material is a dimer fatty acid. For the sample reported above the residue had an acid number of 300, a saponification number of 304, a Gardner color of 16, and a Gardner viscosity of more than Z-6.

The residual dicarboxylic acid fraction was distilled at 270° C. at 0.2 mm. to obtain a somewhat purer dicarboxylic acid. However, at these high temperatures (300° C. pot temperature) decomposition of the dicarboxylic acid began to occur. One of the ways for purifying the dicarboxylic acid is to convert it to its dimethyl ester and then distill this. The competitive distillation temperatures of various esters are reported in Table II.

TABLE II

[Distillation temperatures for materials in the dicarboxylic acid system]

	Pot temp. (° C.)	Vapor temp. (° C.)	Vacuum (mm.)
Fatty acid monomer	200	190	0.2
Dicarboxylic acid	300	265	0.2
Fatty acid methyl ester	185	170	0.2
Monomethyl ester of dicarboxylic acid	265	240	0.2
Dimethyl ester of dicarboxylic acid	235	220	0.2
Dimethyl ester of dimer acid	285	260	0.2

As is illustrated by the results in Table II, by preparing the dimethyl ester of dicarboxylic acid and purifying it by distillation, the fatty acid monomer and the dimer acids can be cleanly removed. In a sample treated in this

manner and then reacidified, the gas chromatograph showed the sample to be 93% dicarboxylic acid. It has an acid number of 310.

While the invention has been described and illustrated herein by references to various specific materials, procedures and examples, it is understood that the invention is not restricted to the particular materials, combinations of materials, and procedures selected for that purpose. Numerous variations of such details can be employed, as will be appreciated by those skilled in the art.

What is claimed is:

1. A process for the production of a dicarboxylic acid from a fatty acid mixture containing conjugated linoleic acid non-conjugated linoleic acid comprising, simultaneously reacting both the non-conjugated and conjugated linoleic acid portion of the fatty acid mixture with up to 26% by weight of said fatty acids of acrylic acid and 0.01% to 0.50% by weight of fatty acid mixture of iodine at a temperature between 200° C. and 270° C. to convert the conjugated and non-conjugated linoleic acid portion to a dicarboxylic acid having the formula

15

20

25

wherein one X is hydrogen and the other X is a carboxylic acid group.

2. The process of claim 1 wherein said fatty acid mixture is a tall oil fatty acid mixture.

3. The process of claim 1 wherein said iodine is present at 0.05 to 0.20% by weight and said temperature is between 230° C. and 250° C.

4. The process of claim 1 further comprising, distilling the fatty acid mixture containing dicarboxylic acid and recovering a linoleic free fatty acid fraction and a dicarboxylic acid fraction.
